TUFTING MECHANISM

Charles Kadlec, Oshkosh, Wis., assignor to
 Waite Carpet Company, Oshkosh, Wis., a corporation of Wisconsin

Application October 21, 1929. Serial No. 401,021

24 Claims. (Cl. 112—79)

This invention relates to a tufting mechanism adapted to be incorporated into a sewing machine for the purpose of drawing out the thread in a series of loops and cutting the same to form tufts so that the resulting product will exhibit characteristics of a tufted rug. In mechanism of this class, it is necessary to provide means associated with the needle, for engaging the loop of thread carried down by the needle and holding the loop while the needle recedes and also to provide mechanism for cutting the loop to present the cut ends as the constituents of a tuft in the completed product. In certain prior constructions, independently operated means have been employed for looping and for cutting and also independent means for clamping the loop when formed to prevent it from being drawn back by the recession of the needle. The present invention simplifies the construction by combining the looping and cutting means in such a way as to avoid the necessity for independent clamping means, and the present invention also utilizes the standard feeding mechanism of the sewing machine to assist in the formation and cutting of the loop so that independently movable looping and cutting mechanism is dispensed with.

In the present embodiment of the invention, the tufting features have been shown as combined with needle operating and feeding mechanism of a standard Singer sewing machine, the movements of which readily lend themselves to the requirements of the present invention although the tufting devices might be associated with other sewing machine movements adequate to afford a feed of the required character.

In the drawings:

Figure 1 is an end elevation of the working parts of a Singer sewing machine with the looping and cutting devices of the present invention associated therewith.

Figure 2 is a plan view of the supporting table showing the looper in dotted lines below.

Figures 3, 4, 5 and 6 are details showing the feeding and looping mechanisms in various positions of adjustment during a single cycle of operations.

Figure 7 is an enlarged detail showing the manner in which the loops are formed on the looper and cut by the associated knife.

Figure 8 is a face view of the feed plate and presser foot in the initial position showing in dotted lines the position occupied at the end of a feeding stroke.

And Figure 9 is a detail taken on line 9—9 of Figure 1.

The mechanism comprises a reciprocating needle 10; a feeding plate 11 and a presser foot 12 which, as shown, are substantially in the form employed in a standard Singer sewing machine, although the feeding plate is modified somewhat in a manner shortly to be described. The needle is carried by a reciprocating needle rod 13 and the feed plate is carried by a reciprocating feed rod 14. The needle rod and the feed rod operate to some extent in unison and are mounted to afford a four-way motion during the course of which the feed plate will be initially lifted and thrust rearwardly while the needle is also lifted, after which the feed plate and needle will descend together, the needle, however, being given a much longer stroke in order to pierce the fabric and carry through the loop-forming thread or yarn. Thereafter, both needle and feed plate will move to feed the fabric forwardly or to the left in Fig. 1, which feeding action serves to draw the yarn loop across the point 15 of a bill-shaped looper 16. The looper is of relatively thin formation so that it will not tend unduly to spread the loop and to one side of the bill-shaped looper is removably secured a knife blade 17, preferably having a razor-like edge projecting slightly below the looper and at a slight obliquity to the line of movement of the loops and in position to engage the advancing loop and hold the same against the recession of the needle and ultimately sever the loop to produce the tuft.

The presser foot 12 operates in alternation to the feed plate 11 and serves to hold the fabric against lifting or withdrawal as the needle and feed plate are elevated. The presser foot is carried at the lower end of a reciprocating presser foot rod 18 and is so disposed, as shown in Figure 9, as to operate within a recess 19 formed through one side of the feed plate. The presser foot is bifurcated to provide a slot 20 through which the needle operates. The feed plate is carried by a bracket 21 mounted at the lower end of the feed plate rod 14, the bracket being pivoted between ears 22, upstanding from the upper or reverse face of the feed plate so that the feed plate will be centrally suspended and permitted to rock more or less to more perfectly adapt it for engagement with the upper surface of the fabric.

The underface of the feed plate and the under face of the presser foot are both serrated, the teeth presenting their abrupt faces in the direction of movement of the fabric which is from right to left in Fig. 1.

The fabric is supported and fed forwardly over

- the surface of a table 23, which is the standard table of a Singer machine and which is provided with an inwardly extending U-shaped recess 24 which receives a plate 25 having a surface flush with the table top, which plate, as shown in Fig. 2 is provided with an elongated slot 26 for the passage of the needle. The plate is also provided with a second aligned slot 27, through which projects the upper edge of a thin gauge plate 28, the body of which projects below the table top and is pivoted by a pin 29 to a lever 30 of the first order, the rear arm of which is upturned and abuts against a coil spring 31, which permits the gauge plate to be depressed under spring tension. The gauge plate serves to afford a line of demarcation between the previously completed lines of tufting and to prevent interference by the tufted surface with the bare fabric presented for a new line of stitching.
- 20 The point of the needle when depressed, bears against the rounded upper surface of a guide head 32 carried upon a post 33 suitably secured to the frame of the table which guide head serves to accurately position the point of the needle with respect to the tip of the looper so that as the needle is carried forwardly in its four-way movement of reciprocation, it will positively carry the newly formed loop onto the tip of the looper as best indicated in Fig. 7.
- 25 The looper is provided with a slot 35 which receives a set screw 36 adapted to clamp the looper in adjusted position upon the frame of the table, and precise adjustment is effected by the manipulation of an adjusting screw member 37, which is held in locked position by a jam nut 38 bearing against the edge of the table.
- 30 A brief résumé of the operating mechanism for the rods 13, 14 and 18 will be given although these parts constitute the standard features of construction of a Singer machine so that detailed description thereof is not deemed necessary. The three rods extend upwardly into a housing 39, which constitutes the end portion of the sewing machine and motion is derived from a disc 40 mounted on the end of the power shaft 41 of the machine.
- 35 Through suitable linkage 42, motion is derived from the rotating disc 40. The rod 13 is provided with a collar 43, which is reciprocated through the linkage 42, and the collar 43 is pivoted to a slide block 44, which is guided within a rectangular guide frame 45, the upper end of which is pivoted at 46 to a sleeve 47, rigidly mounted upon the rod 14 and provided with a head 48 through which the rod 13 is slidably mounted. The frame 45 constitutes one of the arms of a bell crank device, the other arm 49 of which is pivoted to a link 50, the lower end of which is in turn pivoted to a collar 51 which is fast on the rod 18. The rods 13 and 14 are reciprocably mounted through a slide block 52 which is carried by the lower wall of the housing 39 and permits of a limited back and forth horizontal movement commensurate with the feeding back and forth movements imparted to the feed plate and the needle. The upper ends of the rods 13 and 14 are guided through the upper wall of the housing 39 free play being afforded to accommodate back and forth movements of the lower ends of the respective rods.
- 40 This system of links, levers and connections is one which imparts an extended range of reciprocating movement to the needle, and a slight range of reciprocating movement to the feed plate and also imparts to these two instrumentalities

a back and forth movement in unison to effect the feeding of the fabric in conformity with the principle of feeding and needle operation embodied in Singer sewing machines of standard construction.

In operation, with the parts in what may be termed the initial position illustrated in Figure 3, the feed plate and needle will both stand in elevated relation and the presser foot in depressed relation upon the fabric to be tufted. As the needle and feed plate descend, the presser foot will be lifted and the needle will pierce the fabric, carrying with it the thread or yarn until it reaches the position indicated in Figure 4. This brings the needle into guiding contact with the curved surface of the guide head 32 and into immediate proximity with the tip of the looper. With the parts in this position, the needle and feed plate in unison will move forwardly to the position indicated in Figure 5 and this will carry the impaled fabric forward under the conjoint feeding action of the feed plate and the needle and will also carry the loop onto the tip of the looper so that the loop will be spread and held against withdrawal upon the final recession of the needle which occurs as the presser foot descends to re-engage the fabric. This is the position as indicated in Figure 6 and before the feed plate and needle have moved rearwardly to again resume the feeding operation.

As successive loops are thus formed and carried along with the feeding of the fabric, the loops will be crowded against one another and will be drawn along the razor-like edge of the cutting knife and thus severed and transformed into tufts and released from the looper. It is this action in utilizing the feed for the fabric to draw the loops onto and along the looper, which permits a stationary looper and combined knife to be employed in lieu of movable looping and cutting elements with a corresponding simplification in structure and a resulting precision in operation. The tufts as cut will progress forwardly with the advancing fabric and be lifted out through the slot 26 so that they will in no way interfere with the action of the needle and looper in the formation of successive loops. The gauge plate 28 will serve to press the previously formed line of tufts away from the bare fabric presented to the needle and at the same time assist in maintaining a straight line of advance in the formation of a new line of stitching. The device as a whole is extremely simple in construction and may be readily applied to sewing machines of standard construction, with but slight modification which consists mainly in the substitution of the looping elements below the table in place of standard stitching devices customarily provided at this point.

Although as shown the knife blade is made separable from the looper which facilitates sharpening and is otherwise a convenient arrangement, it is not the intention to limit the invention to this arrangement since the looper itself might be sharpened along its under edge and thus sub-serve the purpose of a knife in severing the loops. Other modifications in detail also may be introduced without departing from the spirit of the invention.

I claim:

1. In a tufting mechanism of the class described, the combination with a reciprocating needle, a bill shaped looping device presenting its free end toward the line of reciprocation of the needle, a knife presenting its cutting edge to the

- line of movement of loops formed around the looping device and feeding means associated with the needle and adapted to feed the fabric forwardly and to carry the loops over the free end 5 of the looper and along the cutting edge of the knife to sever the same and form tufts.
2. In a tufting mechanism of the class described, the combination with a reciprocating needle, a looping device in co-acting relation with the needle, a knife presenting its cutting edge to 10 the line of movement of loops formed around the looping device and feeding means associated with the needle and adapted to feed the fabric forwardly and to carry the loops onto the looper and 15 along the cutting edge of the knife to sever the same and form tufts, said feeding means including a feeding plate and a presser foot adapted to engage the fabric in alternation to one another.
3. In a tufting mechanism of the class described, the combination with a reciprocating 20 needle, a looping device in co-acting relation with the needle, a knife presenting its cutting edge to the line of movement of loops formed around the looping device and feeding means associated with the needle and adapted to feed the fabric 25 forwardly and to carry the loops onto the looper and along the cutting edge of the knife to sever the same and form tufts, said feeding means including a feeding plate and a presser foot adapt- 30 ed to engage the fabric in alternation to one another; means for reciprocating the needle and feeding plate in unison through different ranges of movement and for imparting back and forth feeding movements in unison to the feeding plate 35 and needle; and means for reciprocating the presser foot in alternation to the reciprocating movements of the feeding plate.
4. In a tufting mechanism of the class described, the combination with a needle, a fixed 40 looping device having a cutting edge associated therewith, a guide for the tip of the needle to maintain the same when lowered in closely adjacent relation to the tip of the looper to present a newly formed loop thereto; means for reciprocating the needle; and means for feeding fabric and carrying the loops onto the looper and along the cutting edge with the advance of the fabric.
5. In a tufting mechanism of the class described, the combination with a needle, a fixed 50 looping device having a cutting edge associated therewith, a guide for the tip of the needle to maintain the same when lowered in closely adjacent relation to the tip of the looper to present a newly formed loop thereto; means for reciprocating the needle; means for feeding fabric and carrying the loops onto the looper and along the cutting edge with the advance of the fabric; and a gauge plate in proximate relation to the needle 55 and in position to block off the previously formed tufts from the newly presented fabric.
6. In a tufting mechanism of the class described, the combination of a reciprocating needle, a bill-shaped looping device presenting its point in proximate relation to the tip of the needle when pressed downwardly, said looper having a 60 knife edge along its under surface; feeding means having a four-way movement and adapted to advance the fabric and means for imparting a similar four-way movement to the needle to carry the point thereof in transverse relation to the point of the looper to introduce a loop thereonto.
7. In a tufting mechanism of the class described, the combination of a reciprocating needle, a bill-shaped looping device presenting its 65 point in proximate relation to the tip of the 70
- needle when pressed downwardly, said looper having a knife edge along its under surface; feeding means having a four-way movement and adapted to advance the fabric and means for imparting a similar four-way movement to the needle to carry the point thereof in transverse relation to the point of the looper to introduce the loop thereonto, and a presser foot; and means for imparting reciprocating movements thereto in alternation to the reciprocating movements first described. 80
8. In a tufting mechanism of the class described, the combination of a reciprocating needle, a bill-shaped looping device presenting its point in proximate relation to the tip of the needle when pressed downwardly, said looper having a knife edge along its under surface; feeding means having a four-way movement and adapted to advance the fabric and means for imparting a similar four-way movement to the needle to carry the point thereof in transverse relation to the point of the looper to introduce the loop thereonto, a presser foot, means for imparting reciprocating movements thereto in alternation to the reciprocating movements first described; and a 90 yieldable gauge plate in proximate relation to the needle and in position to hold the previously formed line of tufting away from interference with the needle. 95
9. In a tufting mechanism of the class described, the combination of a reciprocating needle, a bill-shaped looping device presenting its point in proximate relation to the tip of the needle when pressed downwardly, said looper having a knife edge along its under surface; feeding means having a four-way movement and adapted to advance the fabric and means for imparting a similar four-way movement to the needle to carry the point thereof in transverse relation to the point of the looper to introduce the loop thereonto, a presser foot, means for imparting reciprocating movements thereto in alternation to the reciprocating movements first described; and a 100 guide head positioned to present its surface laterally to the point of the needle when thrust downwardly and adapted to maintain the point of the needle in alignment with the tip of the looper when introducing a new loop thereonto. 105
10. In a tufting mechanism of the class described, the combination of a reciprocating needle, a bill-shaped looping device presenting its point in proximate relation to the tip of the needle when pressed downwardly, said looper having a knife edge along its under surface; feeding means having a four-way movement and adapted to advance the fabric and means for imparting a similar four-way movement to the needle to carry the point thereof in transverse relation to the point of the looper to introduce the loop thereonto, a presser foot, means for imparting reciprocating movements thereto in alternation to the reciprocating movements first described; and a 115 yieldable gauge plate in proximate relation to the needle and in position to hold the previously formed line of tufting away from interference with the needle; and a guide head positioned to present its surface laterally to the point of the needle when thrust downwardly and adapted to maintain the point of the needle in alignment with the tip of the looper when introducing a new loop thereonto. 120
11. The method of tufting a fabric which consists in stitching with a needle to carry successive turns of yarn through the fabric, advancing the fabric to carry the turns of yarn successively for- 130
- 125
- 130
- 135
- 140
- 145
- 150

- ward onto an edged member to restrain the turns of the yarn during the withdrawal of the needle in the formation of loops, and continuing the advancement of the fabric to draw the loops forward along the edged member to sever the same in the formation of tufts.
12. In a tufting mechanism of the class described, the combination of a reciprocating needle, a bill-shaped looper presenting its free end toward the line of reciprocation of the needle and provided with a cutting edge standing in oblique relation to the line of advance of the fabric and presenting said cutting edge to the line of movement of the loops formed around the looper, and feeding means associated with the needle and adapted to feed the fabric forwardly and to carry the loops over the free end of the looper and along the cutting edge to sever the same and form tufts.
13. In a tufting mechanism of the class described, the combination of a reciprocating needle, a looper in coacting relation with the needle and provided with a cutting edge standing in oblique relation to the line of advance of the fabric and presenting said cutting edge to the line of movement of the loops formed around the looper, and feeding means associated with the needle and adapted to feed the fabric forwardly and to carry the loops to the looper and along the cutting edge to sever the same and form tufts, said feeding means including a feeding plate and a presser foot adapted to engage the fabric in alternation to one another.
14. In a tufting mechanism of the class described, the combination of a needle, a fixed looper having a cutting edge standing in oblique relation to the line of advance of the fabric, a guide for the tip of the needle to maintain the same when lowered into closely adjacent relation to the tip of the looper to present a newly formed loop thereto, means for reciprocating and forwardly feeding the needle to introduce the loops onto the looper, and means for feeding the fabric and carrying the loops along the cutting edge with the advance of the fabric.
15. In a tufting mechanism of the class described, the combination of a reciprocating needle, a stationary looping device in coacting relation with the needle, a guide for the tip of the needle to maintain the same when lowered in closely adjacent relation to the tip of the looping device, to present a newly formed loop thereto, means for intermittently advancing the needle when lowered to carry the loops onto the looping device, a knife carried by the looping device and presenting its cutting edge to the loops formed around the looping device, and means for effecting relative movement between the loops and the cutting edge to sever the loops and form tufts.
16. In apparatus for applying pile loops to a backing sheet, a reciprocatory thread carrying and sheet puncturing needle, in combination with a stationary looper blade for cooperation with said needle in forming, retaining and tightening the loops and determining the length thereof, said needle being relatively movable to directly deliver each initiated loop under and onto said blade.
17. In tufting apparatus, a stationary free-end looper blade arranged under the fabric back to be punctured by the pile thread carrying needle in applying pile loops thereto, in combination with a reciprocatory puncturing pile thread carrying needle relatively movable to cooperate with the free end of said blade in directly passing the thread carried by the needle onto and under said blade end and in tightening and pulling the same rearwardly on said blade.
18. Apparatus for applying series of pile loops to a backing sheet, embodying means to advance said sheet step by step; a pile thread-carrying needle longitudinally reciprocatory to puncture said sheet after each feed stroke of the sheet to carry the loop forming thread therethrough; means to move said needle laterally when extending through the sheet with each forward feeding step of said sheet and to move the needle laterally on its return lateral stroke while withdrawn from said sheet; and a stationary looper on which the looped thread is threaded by said lateral movement of the needle with the advancing movement of said sheet.
19. Apparatus for applying pile loops to backing sheets, embodying feeding means to positively advance the sheet, in which the pile thread is to be stitched to form pile loops or tufts, step by step; a stationary pile thread looper and retainer longitudinally arranged under the path traveled by said sheet and having a free front end; and a pile thread-carrying needle having an eye near its point and reciprocatory for puncturing said sheet and carrying a loop of the pile thread therethrough, said needle being relatively movable and cooperating with the free end of the looper to thread successive pile thread loops on and under said end and to tighten the loops on said looper as the sheet advances step by step.
20. In combination; a pile-thread-carrying and backing-sheet-puncturing needle; actuating means for said needle; a stationary looper blade to cooperate with the needle in threading the successive pile thread loops on the blade with the closed ends of the loops stretched across the under longitudinal edge of the blade and traveling rearwardly thereon as the backing sheet advances, and means for severing said closed ends of the successive loops as they move rearwardly on said blade.
21. The combination in a sewing machine with a needle having reciprocatory movement to form loops from yarn incident to passage through fabric being worked upon, and also having lateral movement incident to progressive feeding of the fabric; of tufting means including a stationary element adapt'd to receive and hold loops successively presented to it by the needle as the same moves laterally in the manner aforesaid.
22. The combination in a sewing machine with a needle having reciprocatory movement to form loops from yarn incident to passage through the fabric being worked upon, and also having lateral movement incident to progressive feeding of the fabric; of tufting means including an element to receive and hold loops successively presented to it by the needle as the same moves laterally as aforesaid, and means to sever the loops while held by said element.
23. In combination, feeding means for positively advancing step by step the backing sheet in which a pile thread is to be stitched to form a succession of pile loops or tufts, a pile thread-carrying and sheet-puncturing needle having an eye for said thread, said needle being periodically movable transversely through said sheet to carry a loop of thread through the sheet and to return through the sheet, a relatively fixed looper co-operating with said needle to receive and hold each loop during an advancing step of said sheet under the positive feeding action of said feeding means, said needle being relatively

movable to slip each initiated loop directly onto said looper.

24. In combination, a pile thread-carrying needle having an eye for the thread, said needle being reciprocatory for puncturing the backing sheet and returning therefrom to stitch the thread therethrough in the form of loops, means to move said needle laterally forward with the sheet while the needle extends through the sheet 10 and the sheet is advancing on a feeding stroke

and to return the needle laterally while withdrawn from the sheet, means to periodically positively advance said sheet step by step while the needle extends through the sheet, and a relatively stationary looper below the sheet and co-operating with the needle to receive the loops from the needle on the lateral strokes of the needle with the advancing movement of and while extending through the sheet.
